TILTABLE ROTARY POWER-DRIVEN WORK-HOLDING UNIT

Harry A. Skilton, Watertown, Conn.

Application April 10, 1945, Serial No. 587,529

13 Claims. (Cl. 51—237)

1

The present invention relates to work-holding units and relates more particularly to work-holding units of a type wherein a table or other work-carrying member is rotatable about a given axis of rotation and in which the said axis of rotation is tiltable.

The work-holding units of the present invention are primarily designed to hold dies and to turn the same to permit the ready and convenient polishing of their cavities, protuberances, etc., though available for other uses.

One of the objects of the present invention is to provide a superior tiltable rotary power-driven work-holding unit having its axis of rotation tiltable or changeable in position to thus enable work to be turned in the desired path.

Another object of the present invention is to provide a superior work-holding unit of the type referred to in which the power used to rotate the work-carrying member will not materially tend to change the position of the axis of rotation of such member.

A further object of the present invention is to provide a superior tiltable rotary power-driven work-holding unit having its parts so constructed and arranged that the power-drive for the tiltable work-carrying member may be readily disconnected to permit manual rotation of the said member when desired.

Still another object of the present invention is to provide a superior work-holding unit of the type referred to and in which the work-carrying member may be automatically locked against rotation by the shutting-off of the driving-power.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in front elevation of a tiltable rotary power-driven work-holding unit constructed in accordance with the present invention;

Fig. 2 is a side view thereof looking in the direction of the arrow 2 of Fig. 1;

Fig. 3 is a broken vertical sectional view on an enlarged scale and taken on the line 3—3 of Fig. 2;

Fig. 4 is a broken vertical sectional view on an enlarged scale and taken on the line 4—4 of Fig. 1;

2

Fig. 5 is a broken horizontal sectional view taken on the line 5—5 of Fig. 4; and

Fig. 6 is a similar view but taken on the line 6—6 of Fig. 4.

5 The particular work-holding unit herein chosen for purposes of making clear a preferred form of the present invention, includes among its main features a base 10, a tubular standard 11, a mounting-yoke generally designated by the reference character 12, and a work-holding table 13.

10 The tubular standard 11 is arranged vertically and has its lower end firmly anchored in the base 10 and is surmounted at its upper end by the mounting-yoke 12. The said mounting-yoke includes a centrally-depending-stem 14 which is entered into the interior of the upper end of the tubular standard 11 and may be rigidly secured therein in any suitable manner. The mounting-yoke 12 also includes two upwardly-extending 15 laterally-spaced-apart arms 15 and 16 respectively provided at their upper ends with horizontal bearing-passages 17 and 18.

15 Mounted respectively in the bearing-passages 17 and 18 above referred to, are the tubular trunnions 19 and 20 of a bearing-head generally designated by the reference character 21. The said tubular trunnions 19 and 20 are axially aligned with each other but project outwardly from the respective opposite sides of the said bearing-head 21, as is especially well shown in Figs. 3 and 5.

20 The said tubular trunnions 19 and 20 are axially in line with each other and respectively project outwardly from the opposite ends of a lug-like trunnion-portion 22 of the said bearing-head 21. The said bearing-head also includes a tubular spindle-portion 23 formed integral with the said trunnion-portion 22 but having its axis extending at a right angle with respect to the axes of the 25 tubular trunnions 19 and 20.

25 Bearing in the spindle-portion 23 of the bearing-head 21 with capacity for rotation therein, is a work-carrying spindle 24 formed at its upper end with an externally-threaded stem 25 onto 30 which the disk-like work-holding table 13 is mounted. At the lower end of its threaded-stem 25, the spindle 24 is formed with a radially-extending integral annular-collar 27 against the upper face of which the hub 26 of the table 13 engages. The under face of the integral-collar 27 bears upon the upper face of the hollow spindle-portion 23 of the bearing-head, as is especially well shown in Fig. 4.

35 The extreme lower end of the spindle 24 bears 40 in the lower portion of a cap 28 forming a clo-

sure for the other otherwise-open lower end of the hollow interior of the spindle-portion 23 of the bearing-head 21. The said cap is formed with an integral upwardly-extending annular-flange 29 having its outer periphery snugly fitting the interior of the spindle-portion 23, as is shown in Figs. 4 and 6.

The internal diameter of the sleeve-like flange 29 of the cap 28 is sufficiently larger than the external diameter of the lower portion of spindle 24 as to be able to accommodate within it a bushing 30. In its upper edge the bushing 30 is formed with two radial clearance-notches 31—31 respectively located at diametrically-opposite points in the bushing 30 and intersecting the upper edge thereof.

The clearance-notches 31—31 in the bushing 30 are adapted to respectively receive the opposite ends of a bar-like coupling-key 32 which extends lengthwise through a diametrical-passage 33 formed in the lower-portion of the spindle 24. The said passage 33 has a vertical extent but slightly less than double the vertical extent of the coupling-key 32 for the purpose of permitting the said coupling-key to be bodily moved vertically, for purposes as will hereinafter appear.

Resting upon the upper edge of the bushing 30 is the lower edge of a hub 34 formed integral with and depending from a worm-wheel 35. The unit consisting of the said worm-wheel 35 and its hub 34 is formed with an axial bearing-passage which fits the periphery of the spindle 24 with freedom for rotation relative thereto and for purposes as will hereinafter appear. The hub 34 is formed in its lower edge with two radial and downwardly-opening coupling-notches or recesses 36—36 respectively located at diametrically-opposite points and adapted to receive the respective opposite ends of the coupling-key 32, for purposes as will hereinafter appear.

The worm-wheel 35 meshes with and is driven by a worm 37 extending horizontally in the trunnion-portion 22 of the bearing-head 21, as is especially well shown in Figs. 3, 4 and 5. Respectively extending outwardly from the opposite ends of the worm 37 are stub-shafts 38 and 39 both forming a rigid feature of the said worm and arranged coaxially with respect thereto. The stub-shafts 38 and 39 respectively turn in the interiors of the tubular trunnions 19 and 20 of the bearing-head 21.

The outer end of the stub-shaft 39 of the worm 37 has rigidly mounted thereon a V-belt pulley 40 which may have a plurality of grooves therein respectively of different diameters and which is adapted to receive a V-belt 41 which serves to drive the said pulley 40 and hence also to drive the worm 37. The lower-portion of the V-belt 41 extends around a V-belt pulley 42 which may also have a plurality of grooves of different diameters respectively and which is mounted upon and driven by the drive-shaft 43 of an electric motor 44. The said electric motor 44 is supported on the upper surface of a motor-bracket 45 adjacent the outer end thereof. The said motor-bracket is formed at its inner end with a tubular-portion 46 through which the lower-portion of the tubular standard 11 extends. The said motor-bracket 45 may, if desired, be vertically adjusted on the standard 11 to suitably regulate the tension of the V-belt 41 or its equivalent.

The tubular trunnion 19 of the bearing-head 21 projects axially beyond the arm 15 of the mounting-yoke 12 and is externally threaded as at 47 to threadedly receive a lock-nut 48. The

said lock-nut is provided with a rigid radially-extending arm 49 which latter terminates at its outer end in a ball-grip 50.

Returning now to the bar-like coupling-key 32 which extends diametrically within the spindle-portion 23 of the bearing-head 21, it will be noted by reference to Fig. 4 in particular, that the said key has centrally threaded into it, the upper end of an operating-plunger 51 which is mounted for reciprocation lengthwise of itself axially in the lower-portion of the spindle 24. The lower-portion of the said operating-plunger extends below the lower end of the spindle 24 and is provided with a handle 52 which is accommodated partly or wholly within the space between the vertical arms 15 and 16 of the normally-stationary mounting-yoke 12, dependent upon the position to which the entire bearing-head 21 is tilted.

For the purpose of yieldingly holding the operating-plunger 51 in either one of two vertical positions, the said operating-plunger is formed in its periphery with two annular detent-grooves respectively designated by the reference characters 53 and 54. The said detent-grooves are alternately adapted to receive a ball-detent 55 mounted in a radial-passage 56 formed in the lower-portion of the spindle 24, as is shown in Fig. 4. The said ball-detent is urged toward the operating-plunger 51 by a helical detent-spring 57.

The bearing-head 21 is preferably formed with a rearwardly-extending integral arm 58 projecting through the space between the complementary arms 15 and 16 of the mounting-yoke 12. At its rear end the said arm 58 has the upper end of a rod 59 rigidly coupled to it. Mounted on the rod with capacity for vertical adjustment is a counterweight 60, for purposes as will hereinafter appear.

Encircling the upper-portion of the tubular standard 11 is the hub 61 forming an integral feature of a radially-extending bracket 62 upon which may be conveniently mounted a suitable motor-driven flexible-shaft unit (not shown) to be utilized for grinding or polishing such dies as may be secured to the upper face of the work-holding table 13 before referred to.

Operation

For purposes of description, let it be assumed that the coupling-key 32 is in its lowermost position as shown in Fig. 4 and that the electric motor 44 is energized.

Under the above described conditions the motor 44 through the intermediary of the V-belt 41, pulley 40 and stub-shaft 39, turn the worm 37. The worm 37 will drive the worm-wheel 35 which under these conditions will turn loosely on the work-carrying spindle 24, inasmuch as the coupling-key 32 is disengaged from the coupling-notches 36—36 in the hub 34 of the said worm-wheel.

Should it now be desired to drive the work-holding table 13, the coupling-key 32 may be shifted upwardly into the coupling-notches 36—36 in the hub 34, by pressing upwardly upon the handle 52 of the operating-plunger 51. As soon as the coupling-key 32 enters the said coupling-notches 36—36, it will be coupled to and driven by the worm-wheel 35 and since it extends through the diametrical passage 33 the said coupling-key will in turn drive the spindle 24 and hence also the table 13. Thus a die or other article secured to the upper surface of the table 13 may be turned while being polished, dressed or otherwise operated upon.

Should it be desired to tilt the table 13 so as to cause the same to rotate about an inclined axis, the lock-nut 48 on the tubular trunnion 19 of the bearing-head 21, may be loosened. Following this operation the entire bearing-head 21 may be turned about the worm as a center during which operation the tubular trunnions 19 and 20 will turn respectively in the bearing-passages 17 and 18 of the mounting-yoke 12. After the bearing-head 21 and the parts carried thereby have been tilted into the desired position, the lock-nut 48 may again be tightened by means of its arm 49 whereupon the new setting of the said bearing-head may be fixed. During the tilting of the bearing-head 21 and the parts carried thereby, the counterweight 60 carried by its arm 58 and rod 59 will, when the said counterweight is properly adjusted, render the said bearing-head and parts carried thereby sufficiently stable so that the same will not of their own weight materially tend to shift.

Now should it be desired for any reason to lock the table 13 against rotation while a special operation is being performed, all that is required is to stop the electric motor 44 whereupon the self-locking engagement between the worm-wheel 35 and the worm 37 will serve this purpose.

Should it be desired to leave the work-holding table 13 free for manual rotation, all that is required to effect this result is to lower the coupling-key 32 into the position in which it is shown in Fig. 4, to thereby uncouple the spindle 24 from the worm-wheel 35. The uncoupling just referred to, may be achieved whether or not the worm-wheel 35 is at the time being driven.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A tiltable rotary power-driven work-holding unit, including in combination: a support having a bearing; a tiltable bearing-head having a tubular trunnion mounted for oscillation in the bearing of the said support; a first gear-member carried by the said bearing-head adjacent the inner end of its said tubular trunnion; drive-means projecting through the tubular trunnion of the said bearing-head and connected to the said first gear-member for driving the same; a work-carrying spindle mounted in the said bearing-head for rotation about an axis disposed at an angle with respect to the axis of the tubular trunnion of the bearing-head; a second gear-member also carried by the said bearing-head and meshing with the said first gear-member; and releasable coupling-means operatively interposed between the said drive-means and the said spindle to selectively connect and disconnect the same; the said bearing-head, second gear-member and work-carrying spindle being jointly tiltable about the axis of the said tubular trunnion.

2. A tiltable rotary power-driven work-holding unit, including in combination: a support having a substantially-horizontal bearing; a tiltable bearing-head having a tubular trunnion mounted for oscillation in the substantially-horizontal bearing of the said support; a first gear-member carried by the said bearing-head adjacent the

inner end of its said tubular trunnion; drive-means projecting through the tubular trunnion of the said bearing-head and connected to the said first gear-member for driving the same; a substantially-vertical work-carrying spindle mounted in the said bearing-head for rotation about an axis disposed at substantially a right angle with respect to the axis of the tubular trunnion of the bearing-head; a second gear-member also carried by the said bearing-head and meshing with the said first gear-member; and releasable coupling-means operatively interposed between the said drive-means and the said substantially-vertical spindle to selectively connect and disconnect the same; the said bearing-head, second gear-member and work-carrying spindle being jointly tiltable about the axis of the said tubular trunnion.

3. A tiltable rotary power-driven work-holding unit, including in combination: a support having two axially-spaced-apart bearings; a tiltable bearing-head having two axially-spaced-apart tubular trunnions respectively mounted for oscillation in the bearings of the said support; a first gear-member carried by the said bearing-head and located intermediate the respective inner ends of the tubular trunnions thereof; drive-means projecting through one of the tubular trunnions of the said bearing-head and connected to the said first gear-member for driving the same; a spindle mounted in the said bearing-head for rotation about an axis disposed at an angle with respect to the axes of the tubular trunnions of the bearing-head; a second gear-member also carried by the said bearing-head and meshing with the said first gear-member; and releasable coupling-means operatively interposed between the said drive-means and the said spindle to selectively connect and disconnect the same; the said bearing-head, second gear-member and work-carrying spindle being jointly tiltable about the axes of the two said tubular trunnions.

4. A tiltable rotary power-driven work-holding unit, including in combination: a support having two axially-spaced-apart substantially-horizontal bearings; a tiltable bearing-head having two axially-spaced-apart tubular trunnions respectively mounted for oscillation in the substantially-horizontal bearings of the said support; a first gear-member carried by the said bearing-head and located intermediate the respective inner ends of the tubular trunnions thereof; drive-means projecting through one of the tubular trunnions of the said bearing-head and connected to the said first gear-member for driving the same; a substantially-vertical work-carrying spindle mounted in the said bearing-head for rotation about an axis disposed at substantially a right angle with respect to the axes of the said tubular trunnions; a second gear-member also carried by the said bearing-head and meshing with the said first gear-member, the said second gear-member being operatively associated with the said substantially-vertical spindle for turning the same; and releasable coupling-means operatively interposed between the said drive-means and the said substantially-vertical spindle to selectively connect and disconnect the same; the said bearing-head, second gear-member and work-carrying spindle being jointly tiltable about the axes of the two said tubular trunnions.

5. A tiltable rotary power-driven work-holding unit, including in combination: a support having a bearing; a tiltable bearing-head having a tu-

tular trunnion mounted for oscillation in the bearing of the said support; a worm carried by the said bearing-head adjacent the inner end of its said tubular trunnion; drive-means projecting through the tubular trunnion of the said bearing-head and connected to the said worm for driving the same; a work-carrying spindle mounted in the said bearing-head for rotation about an axis disposed to one side of and at an angle with respect to the axis of the tubular trunnion of the bearing-head in non-intersecting relationship thereto; and a worm-wheel also carried by the said bearing-head and meshing with the said worm, the said worm-wheel being operatively associated with the said spindle for turning the same; the said bearing-head, worm-wheel and work-carrying spindle being jointly tiltable about the axis of the said tubular trunnion.

6. A tiltable rotary power-driven work-holding unit, including in combination: a support having a bearing; a tiltable bearing-head having a tubular trunnion mounted for oscillation in the bearing of the said support; a worm carried by the said bearing-head adjacent the inner end of its said tubular trunnion; drive-means projecting through the tubular trunnion of the said bearing-head and connected to the said worm-wheel for driving the same; a work-carrying spindle mounted in the said bearing-head for rotation about an axis disposed at an angle with respect to the axis of the tubular trunnion of the bearing-head; a worm-wheel also carried by the said bearing-head and meshing with the said worm; and releasable coupling-means operatively interposed between the said drive-means and the said spindle to selectively connect and disconnect the same; the said bearing-head, worm-wheel and work-carrying spindle being jointly tiltable about the axis of the said tubular trunnion.

7. A tiltable rotary power-driven work-holding unit, including in combination: a support having a substantially-horizontal bearing; a tiltable bearing-head having a tubular trunnion mounted for oscillation in the substantially-horizontal bearing of the said support; a worm carried by the said bearing-head adjacent the inner end of its said tubular trunnion; drive-means projecting through the tubular trunnion of the said bearing-head and connected to the said worm for driving the same; a substantially-vertical work-carrying spindle mounted in the said bearing-head for rotation about an axis disposed to one side of and at substantially a right angle with respect to the axis of the tubular trunnion of the bearing-head in non-intersecting relationship thereto; and a worm-wheel also carried by the said bearing-head and meshing with the said worm, the said worm-wheel being operatively associated with the said substantially-vertical spindle for turning the same; the said bearing-head, worm-wheel and work-carrying spindle being jointly tiltable about the axis of the said tubular trunnion.

8. A tiltable rotary power-driven work-holding unit, including in combination: a support having a substantially-horizontal bearing; a tiltable bearing-head having a tubular trunnion mounted for oscillation in the substantially-horizontal bearing of the said support; a worm carried by the said bearing-head adjacent the inner end of its said tubular trunnion; drive-means projecting through the tubular trunnion of the said bearing-head and connected to the said worm for driving the same; a substantially-vertical work-carrying spindle mounted in the said bearing-head for rotation about an axis disposed to one

side of and at substantially a right angle with respect to the axis of the tubular trunnion of the bearing-head in non-intersecting relationship thereto; a worm-wheel also carried by the said bearing-head and meshing with the said worm; and releasable coupling-means operatively interposed between the said drive-means and the said substantially-vertical spindle to selectively connect and disconnect the same; the said bearing-head, worm-wheel and work-carrying spindle being jointly tiltable about the axis of the said tubular trunnion.

9. A tiltable rotary power-driven work-holding unit, including in combination: a support having two axially-spaced-apart bearings; a tiltable bearing-head having two axially-spaced-apart tubular trunnions respectively mounted for oscillation in the bearings of the said support; a worm carried by the said bearing-head and located intermediate the respective inner ends of the tubular trunnions thereof; drive-means projecting through one of the tubular trunnions of the said bearing-head and connected to the said worm for driving the same; a work-carrying spindle mounted in the said bearing-head for rotation about an axis disposed to one side of and at an angle with respect to the axes of the tubular trunnions of the bearing-head in non-intersecting relationship thereto; and a worm-wheel also carried by the said bearing-head and meshing with the said worm, the said worm-wheel being operatively associated with the said spindle for turning the same; the said bearing-head, worm-wheel and work-carrying spindle being jointly tiltable about the axes of the two said tubular trunnions.

10. A tiltable rotary power-driven work-holding unit, including in combination: a support having two axially-spaced-apart bearings; a tiltable bearing-head having two axially-spaced-apart tubular trunnions respectively mounted for oscillation in the bearings of the said support; a worm carried by the said bearing-head and located intermediate the respective inner ends of the tubular trunnions thereof; drive-means projecting through one of the tubular trunnions of the said bearing-head and connected to the said worm for driving the same; a spindle mounted in the said bearing-head for rotation about an axis disposed at an angle with respect to the axes of the tubular trunnions of the bearing-head; a worm-wheel also carried by the said bearing-head and meshing with the said worm; and releasable coupling-means operatively interposed between the said drive-means and the said spindle to selectively connect and disconnect the same; the said bearing-head, worm-wheel and work-carrying spindle being jointly tiltable about the axes of the two said tubular trunnions.

11. A tiltable rotary power-driven work-holding unit, including in combination: a support having two axially-spaced-apart substantially-horizontal bearings; a tiltable bearing-head having two axially-spaced-apart tubular trunnions respectively mounted for oscillation in the substantially-horizontal bearings of the said support; a worm carried by the said bearing-head and located intermediate the respective inner ends of the tubular trunnions thereof; drive-means projecting through one of the tubular trunnions of the said bearing-head and connected to the said worm for driving the same; a substantially - vertical work - carrying spindle mounted in the said bearing-head for rotation about an axis disposed to one side of and at sub-

stantially a right angle with respect to the axes of the said tubular trunnions in non-intersecting relationship thereto; and a worm-wheel also carried by the said bearing-head and meshing with the said worm, the said worm-wheel being operatively associated with the said substantially-vertical spindle for turning the same; the said bearing-head, worm-wheel and work-carrying spindle being jointly tilttable about the axes of the two said tubular trunnions.

12. A tilttable rotary power-driven work-holding unit, including in combination: a support having two axially-spaced-apart substantially-horizontal bearings; a tilttable bearing-head having two axially-spaced-apart tubular trunnions respectively mounted for oscillation in the substantially-horizontal bearings of the said support; a worm carried by the said bearing-head and located intermediate the respective inner ends of the tubular trunnions thereof; drive-means projecting through one of the tubular trunnions of the said bearing-head and connected to the said worm for driving the same; a substantially-vertical work-carrying spindle mounted in the said bearing-head for rotation about an axis disposed at substantially a right angle with respect to the axes of the said tubular trunnions; a worm-wheel also carried by the said bearing-head and meshing with the said worm, the said worm-wheel being operatively associated with the said substantially-vertical spindle for turning the same; and releasable coupling-means operatively interposed between the said drive-means and the

said substantially-vertical spindle to selectively connect and disconnect the same; the said bearing-head, worm-wheel and work-carrying spindle being jointly tilttable about the axes of the two said tubular trunnions.

13. A tilttable rotary power-driven work-holding unit, including in combination: a support having a bearing; a tilttable bearing-head having a tubular trunnion mounted for oscillation in the bearing of the said support; a first gear-member carried by the said bearing-head adjacent the inner end of its said tubular trunnion; drive-means projecting through the tubular trunnion of the said bearing-head and connected to the said first gear-member for driving the same; a work-carrying spindle mounted in the said bearing-head for rotation about an axis disposed at an angle with respect to the axis of the tubular trunnion of the bearing-head, the said spindle being formed with a transverse key-receiving passage; a second gear-member encircling the said spindle and meshing with the said first gear-member, the said second gear-member being formed with a key-receiving notch; and a transverse coupling-key extending transversely through the said spindle and movable in a direction paralleling the axis of the said spindle into and out of the key-receiving notch in the said second gear-member to respectively couple and uncouple the said second gear-member from the said spindle.

HARRY A. SKILTON.
